INVENTOR.

GUSTAVE H. SCHMIDT.

BY

Albert C. Bell

ATTORNEY.

UNITED STATES PATENT OFFICE.

GUSTAVE H. SCHMIDT, OF CHICAGO, ILLINOIS.

DETACHABLE HEEL.

Application filed October 13, 1927. Serial No. 225,882.

My invention relates to an improved form of detachable heel for shoes, by which heels of rubber may readily be placed on shoes equipped to receive them and readily removed without the use of tools of any kind. My construction further provides that the heels of the right and left shoes of any pair may be interchanged as desired to equalize wear and that the retaining devices are entirely concealed when the heels are locked in place on the shoes.

My invention will best be understood by reference to the accompanying drawings showing a preferred embodiment thereof in which

Fig. 1 illustrates a part of a shoe in side elevation with my heel in place thereon,

Fig. 2 is a sectional view to an enlarged scale, of the parts shown in Fig. 1, taken along the line 2—2.

Fig. 3 is a plan view of the parts shown in Fig. 2 with the shoe removed and with the heel in section to show part of the retaining anchors employed, and

Fig. 4 is a rear elevation of the retaining devices shown in Fig. 3, with the material of the heel shown in section to more clearly disclose the retaining devices.

Similar numerals refer to similar parts throughout the several views.

As shown in Figs. 2, 3 and 4 my construction consists of a plate 10 to be secured to the heel portion 11 of a shoe by screws 12, the edges of the plate 10 indicated at 13, 13 being of reduced thickness to form tongues entering corresponding grooves formed in the inner edges of retaining members 14, 14 provided with anchors 15 and 16 embedded in the material of the heel 17. As indicated in Fig. 3, the retaining members 14, 14 extend throughout the length of the heel 17 and are curved at their rear ends to the conformation of the rear end of the plate 10, and as more clearly shown in Fig. 4, one of the members 14 is provided at its rear end with a projecting tongue 18 entering a corresponding end groove 19 in the other retaining member 14. This tongue and groove engagement permits a hinge action at the rear end of the retaining members for a purpose to be described. The anchors 15 extend outwardly from each of the members 14 and are embedded in the material of the heel 17 while the anchors 16 extend downwardly and

inwardly to distribute the engagement between the material of the heel and the members 14.

Each of the members 14 is provided in its edge groove with a projecting lug 20 for entering a corresponding notch 21 in the edge of one of the tongues 13 when the heel is in place on the shoe. A thin wall 22 of the heel 17 is continued above the front ends of the plate 10 and the members 14 to conceal these parts when the heel is in place on the shoe as shown in Fig. 1.

The material of the heel may be of any convenient kind for the purpose, for example rubber compound, the principal requisite being that it shall have sufficient resilience to serve as a cushion heel and at the same time permit sufficient separation of the members 14 from each other at their front ends when the heel is slid onto the plate 10, to permit the lugs 20 to pass over the outer edges of the tongues 13 and engage the notches 21, which engagement locks the heel in place on the plate 10. For this operation, the thin wall 22 is of course stretched down around the lower surface of the plate 10 until the heel is in place on the shoe when it assumes the position indicated in Fig. 1. To remove the heel from the shoe, the members 14 of the heel are sprung outwardly at their front end to sufficiently release the lugs 20 from the notches 21 when the heel may be slid rearwardly from the plate 10.

It will be observed that the tongues 13 extend from the side edges of the plate 10 around its rear end and that the grooves 19 in the members 14 are similarly formed, as a result of which when the retaining members are in the position indicated in Fig. 3 on the plate 10, to hold the heel on the shoe, the retaining members are securely held in substantially the plane of the plate 10 and thus lateral stiffness and support is imparted to the resilient material of the heel through the anchors 15 and 16 extending therefrom. The plate and retaining members are preferably made of cast metal of sufficient strength and stiffness to perform their intended function, for example aluminum alloy or brass. The material of the heel 17 is preferably so related to the upper surfaces of the members 14 that it presses into close engagement with the bottom of the heel portion of the shoe when the heel

is in place on the shoe and thus a practically water tight joint is produced between the heel and the shoe when the heel is in use.

It will be observed that the parts of the device are simple and cheap in construction and efficient in use and that when the heels are worn over on one edge or another they may be interchanged on any pair of shoes and further that when the heels are worn out they may be replaced without difficulty and without the use of tools of any kind to remove the heels from the shoes or place them on the shoes.

While I have shown my invention in the particular embodiment above described, it will be understood that I do not limit myself to this exact construction as I may employ equivalents known to the art at the time of the filing of this application without departing from the scope of the appended claims.

What I claim is:

1. In a detachable heel, the combination of a plate for attachment to a shoe, a heel of resilient material, and retaining members secured to said heel and having a sliding tongue and groove engagement with opposite edges of said plate, said members and said plate having co-operating locking portions to retain said members in engagement with said plate, and said members having interlocking movable engagement with each other at one end to permit engagement and disengagement of said locking portions and tending to hold said retaining members in the same plane, the material of said heel permitting slight separation of said retaining members from each other to engage and release said locking portions and tending to hold said locking portions in locking engagement with each other and to hold said members through said tongue and groove engagement in the plane of said plate.

2. In a detachable heel, the combination of a plate for attachment to a shoe, a heel of resilient material, and retaining members secured to said heel and having a sliding tongue and groove engagement with opposite edges of said plate, said members and said plate having co-operating locking portions to retain said members in engagement with said plate, and said members having interlocking movable engagement with each other at one end to permit engagement and disengagement of said locking portions and tending to hold said retaining members in the same plane, the material of said heel permitting slight separation of said retaining members from each other to engage and release said locking portions and tending to hold said locking portions in locking engagement with each other and to hold said members through said tongue and groove engagement in the plane of said plate, said heel having a protective flap covering the front ends of said

members and the front edge of said plate.

3. In a detachable heel, the combination of a plate for attaching to a shoe, a heel of resilient material, and retaining members having anchor portions embedded in said heel and having a sliding tongue and groove engagement with opposite edges of said plate, said members and said plate having cooperating locking portions to retain said members in engagement with said plate, and said members having interlocking movable engagement with each other at one end to permit engagement and disengagement of said locking portions and tending to hold said retaining members in the same plane, the material of said heel permitting slight separation of said retaining members from each other to engage and release said locking portions and tending to hold said locking portions in locking engagement with each other and to hold said members through said tongue and groove engagement in the plane of said plate.

4. In a detachable heel, the combination of a plate for attachment to a shoe, a heel of resilient material, and retaining members having anchor portions embedded in said heel and having a sliding tongue and groove engagement with opposite edges of said plate, said members and said plate having cooperating locking portions to retain said members in engagement with said plate, and said members having interlocking movable engagement with each other at one end to permit engagement and disengagement of said locking portions and tending to hold said retaining members in the same plane, the material of said heel permitting slight separation of said retaining members from each other to engage and release said locking portions and tending to hold said locking portions in locking engagement with each other and to hold said members through said tongue and groove engagement in the plane of said plate.

5. In a detachable heel, the combination of a plate for attachment to a shoe, a heel of resilient material, and retaining members secured to said heel and having inner edge grooves for sliding engagement with the edges of said plate, said members and said plate having cooperating locking portions in said grooves to retain said members in engagement with said plate, and said members having interlocking movable engagement with each other at one end to permit engagement and disengagement of said locking portions and tending to hold said retaining members in the same plane, the material of said heel permitting slight separation of said retaining members from each other to engage and release said locking portions and tending to hold said locking portions in

locking engagement with each other and to hold said members through said groove engagement in the plane of said plate.

6. In a detachable heel, the combination 5 of a plate for attachment to a shoe, a heel of resilient material, and retaining members secured to said heel and having inner edge grooves for sliding engagement with the edges of said plate, said members and said 10 plate having cooperating locking portions in said grooves to retain said members in engagement with said plate, and said members having interlocking movable engagement with each other at one end to permit engagement 15 and disengagement of said locking portions and tending to hold said retaining members in the same plane, the material of said heel permitting slight separation of said retaining members from each other to engage and release 20 said locking portions and tending to hold said locking portions in locking engagement with each other and to hold said members through said tongue and groove engagement 25 in the plane of said plate.
7. In a detachable heel, the combination 30 of a plate for attachment to a shoe, a heel of resilient material, and retaining members secured to said heel and having a sliding tongue and groove engagement with opposite edges of said plate, said members and said plate having cooperating locking portions 35 to retain said members in engagement with said plate, and said members having a tongue

and groove engagement with each other at one end to permit engagement and disengagement of said locking portions and tending to hold said retaining members in the 40 same plane, the material of said heel permitting slight separation of said retaining members from each other to engage and release said locking portions and tending to hold said locking portions in locking engagement 45 with each other and to hold said members through said tongue and groove engagement in the plane of said plate.

8. In a detachable heel, the combination 50 of a plate for attachment to a shoe, a heel of resilient material, and retaining members secured to said heel and having inner edge grooves for sliding engagement with the edges of said plate, said members and said plate having cooperating locking portions 55 in said grooves to retain said members in engagement with said plate, and said members having a tongue and groove engagement with each other at one end to permit engagement and disengagement of said locking portions and tending to hold said retaining members in the same plane, the material of said heel permitting slight separation of said retaining members from each other to engage 60 and release said locking portions and tending to hold said locking portions in locking engagement with each other and to hold said members through said groove engagement in the plane of said plate.

In witness whereof, I hereunto subscribe 70 my name this 4th day of October, A. D. 1927.

GUSTAVE H. SCHMIDT.
